CLAIM

The ornamental design for a case for electronic devices, as shown and described.

DESCRIPTION

FIG. 1 is a perspective view of a case for electronic devices, having a support leg wherein the support leg is in an open position showing my new design;

FIG. 2 is a front perspective view thereof;

FIG. 3 is a rear elevational view thereof;

FIG. 4 is a front elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is a front perspective view of the support leg in an open position only shown separately for clarity of disclosure;

FIG. 10 is a rear perspective view thereof;

FIG. 11 is another front perspective view thereof;

FIG. 12 is a rear perspective view of the case without the support leg; and

FIG. 13 is a front perspective view thereof;

FIG. 14 is an exploded rear perspective view showing the case and the support leg in an open position; and,

FIG. 15 is a rear perspective view of the case with the support leg in a closed position.

The dashed broken lines depict portions of the case for electronic devices that form no part of the claimed design. The dot-dashed broken lines depict bounds of the claimed design.

1 Claim, 15 Drawing Sheets
